UNITED STATES PATENT OFFICE.

JOHN B. OHLSON, OF CHICAGO, ILLINOIS, ASSIGNOR TO THE VORTEX MFG. CO., OF CHICAGO, ILLINOIS, A CORPORATION OF ILLINOIS.

DISPENSING CONTAINER AND METHOD OF DISPENSING ARTICLES THEREFROM.

Application filed October 18, 1924. Serial No. 744,341.

This invention relates to a dispensing container and method of dispensing articles therefrom and particularly to a device which is adapted for containing a plurality of 5 nested articles such as paper drinking cups which are to be individually removed therefrom as needed for use.

The present application is a continuation in part of my application for patent for a dispensing container, Serial No. 735,227, filed September 2, 1924.

In devices of this kind it is desirable that the articles in the container be protected from contamination by dust and the like and 15 it is also highly desirable that they be positioned at all times ready for convenient individual removal. Devices for this purpose as heretofore provided have not successfully met these requirements in that the articles 20 were not properly protected or were not maintained in position for convenient individual removal.

It is an important object therefore of the present invention to provide a dispensing 25 container which is inexpensive, durable, attractive in appearance and which satisfactorily and effectively meets all the requirements of such devices in commercial use.

It is a further object of this invention to 30 provide a dispensing container wherein the nested articles are at all times submitted to an applied positioning force for retaining the same in proper association with each other for facilitating the convenient individual removal of the articles therefrom.

It is another and important object of this invention to provide a dispensing container of the kind described wherein means automatically movable and not necessarily aided 40 by gravity permit the exteriors of the contained articles to be successively exposed for individual removal.

It is also an important object of this invention to provide a dispensing container which 45 operates effectively with flangeless articles to dispense the same individually.

It is another object of this invention to provide a dispenser of the class described wherein resiliently impelled means are provided for engaging and positioning the articles as the same are withdrawn.

It is an important object of this invention to provide a dispenser for a stack of nested articles and a method of dispensing articles 55 therefrom wherein the stack of articles is

maintained stationary and over the influence of compressing forces in directions parallel to and normal to the axis of the stack.

It is finally an important object of this invention to provide an apparatus of the kind described wherein the stack of articles is stationary, wherein the exposure of successive articles is entirely automatic and wherein there is no objectionable disfigurement of the articles occasioned by such removal. 65

Other and further important objects of this invention will be apparent from the disclosures in the specification and the accompanying drawings.

This invention (in a preferred form) is 70 illustrated in the drawings and hereinafter more fully described.

On the drawings:

Figure 1 is a front elevation of a dispensing container embodying the principles of 75 this invention.

Figure 2 is an enlarged vertical section taken on the line II—II of Figure 1 with parts shown in elevation.

Figure 3 is a section on the line III—III 80 of Figure 2.

Figure 4 is an enlarged fragmentary section on the line IV—IV of Figure 2 with parts omitted.

Figure 5 is a section on the line V—V of 85 Figure 2.

Figure 6 is a fragmentary top plan view of the containing dispenser of this invention showing a stack of conical paper drinking cups being inserted therein; the dotted lines 90 showing the form assumed by said cups after such insertion.

Figure 7 is a view similar to Figure 5 showing a stack of conical paper drinking cups in the container. 95

Figure 8 is an elevational view of a stack of conical cups, the dotted lines showing the form assumed thereby due to the compressing forces normal to the axis of the stack exerted by the container. 100

Figure 9 is a top plan view of the stack shown in Figure 8.

As shown on the drawings:

The reference numeral 1 indicates the body of the container proper which as will be noted, comprises a tubular member of rectangular section built up of suitable pieces of sheet metal, open at its lower end and having a longitudinal opening in its front wall communicating with said lower open end. The 110

upper end of the container is closed with a suitable hinged cover 2 to prevent dust and dirt and other foreign matter from contaminating the articles therein. Secured to the 5 inside of the upper end of the container is a fixed flange or retaining means 3 having an oval-shaped or elliptical opening 4 therein through which the articles to be dispensed by the container may be inserted.

10 In the embodiment of the invention shown in Figures 1 to 5 inclusive this opening is adapted to have inserted therethrough a stack of nested interfitted flat paper drinking cups which are indicated in Figures 1 and 15 5 by the reference numeral 5.

The edges of the flange at the opening 4 are turned downwardly as shown to facilitate the insertion of the stack of articles therethrough.

20 Secured to the inside of the side walls of the container 1 and extending longitudinally thereof are trough-shaped guide members 6 which are adapted to frictionally engage the edges of the cups 5. The rear sides of said 25 trough-shaped members are provided with transverse indentations 7 (Fig. 2) of approximate saw tooth form which aid in the frictional engagement between the edges of the cups in the stack and guide members 6. 30 As will be noted from an examination of Figures 2 and 3, the ends of said guide members are flared outwardly as indicated by the reference numeral 8 in order to facilitate the insertion and removal of the cups and also to 35 strengthen the construction.

The back wall of the container 1 is also provided with transverse saw-tooth like corrugations 7^a which aid in preventing relative upward movement of the stack of articles.

40 The inner longitudinal edges of the front wall of the container along the sides of the opening therein are bent back upon the inner face of the front wall as indicated at 9 to reinforce said edges and secured to the inside 45 of the container adjacent said reinforced edges are channel members 10 which afford guideways for telescopically arranged plates 11 and 12 which are adapted to be moved downwardly in said guideways to close said 50 longitudinal opening in the front of the container and to protect the nest of articles inside the container. Secured to the inside of the plate 12 at the lower end thereof is a 55 plate 13 having a flange member 14 extending angularly and downwardly from the lower edge thereof, said flange member being cut out as indicated at 15 to conform to the contour of the outer surface of the nest of cups which it frictionally engages. Extending inwardly from each side of the plate 13 is a member 16 which terminates in an integral trough-shaped portion 17 which slidably engages in the trough-shaped guide member 6. Connected between one edge of the member 14 60 and a suitable bracket 18 secured to the side

wall of the container directly beneath the flange 3 is a helical spring 19 which acts to normally urge the plate 13 and the member attached thereto toward the top of the container and the flange 3.

Extending toward the rear of the container from the trough-shaped portions 17 are vertical guide members 17^a (Fig. 2) which slidably engage longitudinal guide plates 17^b 75 mounted inside the side walls of the container at the back portion thereof, and hinged between said members 17^b adjacent said connecting member is a cut out member 17^c similar in shape to the flange member 14 and extending inwardly towards said flange member.

80 Bent down guide ears 20 are formed at the upper ends of the members 17 and connected between said guide ears and the members 17^a are helical springs 20^a preferably of less capacity than the springs 19 which tend to pull said members upward into resilient engagement with the lowermost article in the stack 5 whereby said article is positioned by said member as it is withdrawn from the container. Said member 17^c at its extreme upper 90 position abuts cushioning blocks 17^c in the members 16.

When the nest of articles is inserted in the container the same is forced through the oval-shaped opening 4 into engagement with the cut out 15 in the member 14, the edges thereof engaging in the trough-shaped member 17, and the insertion of the stack of cups into such engagement is facilitated by bent down guide ears 20. As the nest of cups is 100 pushed into the container through the opening 4, the plate 13 and the plate 12 move downwardly elongating the springs 19 until the bottom edge of the plate 11 is reached, at which time ears 21 on the upper edge of said 105 plate 12 engage flange ears 22 on the plate 11 and said plate 11 is then forced downwardly until stopped by the engagement of said ears with notches 23 in the channel members 10. (Figures 2 and 4).

110 When the container has thus been filled with articles to be dispensed it will be noted that said articles are held stationary in the container and are also held in association with each other by the tension of the helical springs 19 which, of course, tends to draw the plate 13 and the members attached thereto which frictionally engage the lowermost article of the stack toward the flange 3. It is to be noted that the articles when inserted in position in the container, due to the inherent resiliency thereof, spring outwardly to the lower edge of the flange 3 and consequently can only be removed by pulling them individually from the lower end of the container past the cut out portion 15 of the member 14 and past the cut out portion of the member 17^a.

120 The dispensing container of this invention is adapted to be used in connection with a 130

stack of flat nested articles such as shown at 5 but it will also operate equally effectively to individually dispense articles from a stack of nested articles of a different shape such as

5 for example, a stack of nested conical paper receptacles which I have designated by the reference numeral 24 in Figures 6, 7, 8 and 9. When such articles are forced into the container through the oval-shaped opening 10 4, the stack will, of course, be compressed in a direction normal to its axis and maintained so compressed, and also compressed in a direction parallel to its axis by the springs 19 as the articles are individually dispensed.

15 The dotted lines in Figures 6, 8 and 9 illustrate the form assumed by the stack of cone-shaped receptacles 24 when so compressed and this compression serves to maintain the receptacles in proper position and assures that 20 the removal thereof will be individual. Of course, the same compressive forces sometimes in a lesser degree are applied to the stack of nested articles 5 previously referred to herein.

It will be readily seen that as the articles 25 are individually removed from the container the plates 12 and 11 will be successively moved upwardly by the action of the springs 19 to present or expose successive articles for removal in the manner described. This action is 30 illustrated in dotted lines in Figure 5 which indicates the relative position of the cup during individual withdrawal. The relative position of the lowermost cup and the plates 12 and 11 is clearly shown in Figure 1.

35 It will be apparent that this invention provides a dispensing container wherein the cups or other articles nested therein are held stationary relative to the container and under the compressive forces hereinbefore referred to. The interior of said articles is protected at all times from contamination by dust or other foreign matter. At the same time the telescoping movement of the plates 12 and 11, as the articles are removed from the container 45 by being individually drawn past the members 13 and 17^a, provides for the successive exposure of the lowermost article of the stack for removal until all of the articles are in fact removed from the container.

50 The device provided is inexpensive, attractive in appearance and durable and the articles as removed therefrom are not damaged and as will be apparent are conveniently opened in position for immediate use when withdrawn.

55 I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. The combination with a container adapted to have a stack of nested articles contained

therein, stationary relative to said container, a hinged member engaging the endmost article of the stack, and means supporting said hinge member and forming a part of said container and automatically movable thereto as individual articles are successively removed therefrom.

2. The combination with a container adapted to have a stack of nested articles contained therein and stationary relative to said container, pivoted means in engagement with the endmost article of the stack, and means carrying the pivoted means and automatically movable relative to the container as individual articles are successively removed from the container.

3. The combination with a container adapted to have a stack of nested articles therein, stationary relative to the container, spring actuated means automatically movable into engagement with the lowermost article of the stack as articles are individually removed from the container and article positioning and guiding plate pivotally mounted on said means.

4. The combination with a container adapted to have a stack of nested articles therein, stationary relative to the container, means automatically movable into engagement with the lowermost article of the stack as the articles are successively individually removed from the container, a cut out number pivotally mounted on said last mentioned means, and springs for resiliently holding said cut out member against the lowermost article in said stack.

5. The combination with a container adapted to have a stack of nested articles therein, stationary relative to the container, means automatically movable upwardly into engagement with the endmost article of the stack as the articles are successively individually removed from the bottom of the container, article positioning and guiding means movably mounted on said last mentioned means, and springs connected to said first mentioned means and to said article positioning and guiding means.

6. The combination with a container adapted to have a stack of nested articles therein, a spring actuated follower slidable in the container and automatically maintained in engagement with the lower end of said stack of articles, and article retaining means movably mounted on said follower.

7. The combination with a container adapted to have a stack of articles therein, telescoping follower members in the container, springs connected thereto for automatically maintaining the follower members in engagement with said articles, and spring actuated movable means on said follower also maintained in engagement with said articles.

8. The combination with a container adapted to have a stack of articles therein, an arti-

cle engaging follower in the container, spring means for automatically maintaining said follower in engagement with the articles, movable article positioning and guiding means on the follower, and spring means for maintaining said positioning means in engagement with the articles, said last mentioned spring means being of less capacity than the first mentioned spring means.

10 9. The combination with a container adapt-

ed to have a stack of articles held stationary therein, slidable means automatically movable in the container for successively exposing articles of the stack for individual removal, and spring controlled retaining means pivoted on said slidable means for engaging the side of the lowermost article in said stack. ¹⁵

In testimony whereof I have hereunto subscribed my name.

JOHN B. OHLSON.
